THREAD CLEANER

Willard T. Munson, Dunmore, Pa., assignor to
 Collins Supply & Equipment Company, Scranton, Pa., a copartnership composed of Henry E. Collins and Albert B. Collins

Application December 24, 1936, Serial No. 117,670

2 Claims.

(Cl. 28—70)

My invention relates to an improvement in thread cleaners.

The object of this improvement is to attain maximum efficiency in the cleaning of the thread as it is pulled through the device.

The present invention is the result of extensive experiments with all thicknesses of cleaner blades ranging from one-sixteenth ($\frac{1}{16}$ ") inch thick upward, until the maximum of efficiency was attained.

The invention consists in a combination of relatively wide and narrow blades arranged in pairs, the blades of each pair suitably separated from each other for the passage of the thread, the two sets of blades being disposed at an angle to each other, as for example at right-angles, with more or less definite predetermined space or interval between the two sets of blades.

In the accompanying drawing:

Fig. 1 is a view in perspective;
 Fig. 2 is a view in end elevation;
 Fig. 3 is a view in front elevation;
 Fig. 4 is a top plan view; and
 Fig. 5 is an enlarged vertical section on the line 5—5 of Fig. 4.

The numeral 1 represents a frame, preferably offset along the line 2, to form a supporting plate 3. At the rear, an arm 4 depends and may be an integral part of the frame, and to the lower end of this arm the usual porcelain thread-guide 5 is adjustably secured by means of nuts 6 on the threaded bolt 7. An upturned slotted lug 8 forms a means of attachment to the table or support.

The present invention resides mainly in two sets of cleaner blades, which will now be described.

The numerals 9 and 10 indicate what will be hereinafter designated the wide blades. These are held at one end in a head 11 by means of the set-screw 12, suitably spaced apart and parallel with each other to receive the thread drawn therebetween. The head is pivoted to the frame by means of a screw 13, and the head is provided with a stop 14 in position to engage a stop 15 projecting from the supporting plate 3. The stop 14 engages the stop 15 to limit and define the extreme upward and lower swing or movement of the pivotally mounted head.

A finger 16 extends outwardly more or less parallel with the wide blades 9 and 10 and acts as a guide in cooperation with the porcelain to direct the thread between the blades.

A head 17 is pivoted by means of a screw 18 to the frame 1. Narrow blades 19 are held in the

head 17 by means of the set-screw 20 located in the end of the head as viewed in Figs. 1 and 2. A pair of guides 21 extend outwardly from the head 17 to cooperate in guiding the thread between the blades 19. The inner ends of the narrow blades 19 extend to, and rest against, the lugs 22, which latter project from the head 17 as shown in Figs. 2 and 4. These lugs 22 are in position with respect to the arms 4 to form stops thereagainst to limit the swinging movement of the head 17 on its pivot 18.

Thus from the foregoing it will be seen that there is an arrangement of two sets of blades with the cleaning space or slot between the blades in each pair, or intervening between the blades of each pair, at right-angles to each other, and with a space 25 of more or less defined and definite width between the pairs of wide and narrow blades.

This space is important and has a function. This relatively narrow space 25 between the two sets of blades prevents the thread passing from the wide sets of blades to the narrow set of blades from screwing or twisting out of the flattened condition resulting from passing between the wide blades before entering the space between the two narrow blades.

In arriving at this improvement, extensive experiments were made with varying thicknesses of cleaner blades ranging from one-sixteenth ($\frac{1}{16}$ ") of an inch thick, upwards, until it was found that the highest efficiency was attained by first passing the thread between blades approximately one-half ($\frac{1}{2}$ ") inch wide. Greater widths showed little or no improvement. In other words, the one-half ($\frac{1}{2}$ ") inch wide seemed to afford the maximum efficiency. These were the findings on single cleaning or cleaning between one pair of blades only.

With further experiments it was found by running the thread through different arrangements of two sets of blades, by double cleaning as it is termed, with the cleaning blades or spaces at right-angles to each other, still better results were obtained. Thus by first passing the thread between one-half ($\frac{1}{2}$ ") inch wide blades, and then between another pair of blades, the thickness of which was, apparently, not important, but for economy purposes, one-sixteenth ($\frac{1}{16}$ ") inch thickness, apparently was adequate and about right.

The experiments showed that an important factor was the space or spaces 25 between the two sets of cleaning blades with perhaps the best

results at approximately one-thirty-second ($\frac{1}{32}$ ") of an inch wide or less.

- Further explaining this operation, a defect or enlarged portion in the thread passing between 5 the wide blades becomes flattened to the size of the space between the blades. The thread is also held from screwing or turning by and between these wide blades, the width of the blades having this desired effect.
- 10 The space between the sets of blades is sufficiently narrow to prevent the thread crossing this space from screwing or twisting out of flattened position, a condition resulting from the passage between the wide blades and before entering the space between the second set of blades.
- 15 The passing of the thread from one pair of blades in this flattened condition of the thread with the blades set at right-angles to the thus flattened defect in the thread, causes the thread to break at this point.

20 While the proportions recited have proven desirable, they might, of course, be varied and there is no intention of limiting myself to them, since even different relative proportions might be found 25 advantageous, if not even better.

I claim:

1. The combination of a frame having an offset portion to form a supporting plate, one edge of the plate having a stop formed thereon, a 30 head pivoted to the offset portion and having a stop adjacent to the pivot in position to engage the stop on the plate, whereby to limit the pivotal movement of the head, blades removably

supported in the head, an arm extending laterally from the lower end of the frame, a guide supported on the arm, a second head pivotally supported on the frame and provided with a pair of guides which extend at an angle to the blades 5 held in the first-mentioned head, blades carried by the head having the guides, means for detachably securing said blades in the head, the head having the pair of guides having lugs at one end against which the blades are adapted to rest, said lugs in position with respect to the arm on the frame to form limiting stops thereagainst to limit the pivotal movements of the head.

2. The combination of a frame having a supporting plate at one end and provided with a laterally extending arm for the support of a guide at another point, two heads pivotally mounted, one on the supporting plate and the other on the frame, relatively wide blades removably supported in one head, relatively narrow blades removable supported in the other head, and extending at an angle to the wide blades, said pairs of blades held a very limited and predetermined distance apart to preserve a definite space through which the thread passes from one set of blades to the other before it has a chance to twist or screw, the supporting plate having a stop in position with respect to the head which carries the wide blades to limit the extreme pivotal movements of said head, and the arm supporting the guide in position to limit the extreme pivotal movement of the head carrying the relatively narrow blade.

WILLARD T. MUNSON.
